UNITED STATES PATENT OFFICE.

JOHN J. KUNTZ, OF BROOKLYN, NEW YORK.

SAFETY APPLIANCE FOR ELEVATORS.

1,184,461.

Specification of Letters Patent. Patented May 23, 1916.

Application filed November 7, 1914. Serial No. 870,838.

to whom it may concern:

Be it known that I, JOHN J. KUNTZ, a citizen of the United States, residing at Brooklyn, in the county of Kings and State 5 of New York, have invented certain new and useful Improvements in Safety Appliances for Elevators, of which the following is a full, clear, and exact specification.

This invention relates to safety appliances 10 for elevators, and has for its object to provide improved means for automatically breaking the circuit to the controller of an electric elevator whenever one of the doors to the shaft is left open or unlocked.

15 A special object is to improve the construction of the circuit breaker used in connection with each of the doors leading to the elevator shaft, which circuit breaker will not short circuit in the operation of automatically breaking the circuit to the controller when its door is opened and of closing the circuit again when the door is fully closed and locked.

20 The invention will be first hereinafter described in connection with the accompanying drawings, which constitute a part of this specification, and then more specifically defined in the claim at the end of the specification.

25 In the accompanying drawings, wherein corresponding parts are indicated by similar reference characters throughout the several views: Figure 1 is a diagrammatic view of an elevator shaft with three doors, the middle one of which is open disclosing the controller on the elevator arranged opposite said door, and indicating the circuit from a generator including my improved circuit breakers as well as the controller. Fig. 2 is an interior side view of one of my improved circuit breakers, and Fig. 3 is a cross section of the same taken through the opening in the partition to receive the end of the pin carrying the bridging plate when 30 said plate is pressed into contact with the terminals of the circuit, which occurs when the door is locked.

35 In Fig. 1, A, A' and A² designate the doors to an elevator shaft B, and C indicates the controller on the elevator which, as shown, is arranged opposite the open door A'. D, B' and D² designate my improved circuit breakers applied to the frame of each of the doors. Each circuit breaker 40 has a spring leaf E which is pressed inward so as to close the circuit when the

door is closed and locked, but which automatically springs outward and breaks the circuit when released by the unlocking and opening of the door. The circuit from the generator F is through conductor G which includes the motor G' to the top one of the circuit breakers, by conductor H from this circuit breaker to the next one, by conductor I from the second circuit breaker to a fixed point c, by looped conductor J from said fixed point c to the controller, by looped conductor J' from the controller to a fixed point c', by conductor I' from the point c' to the third circuit breaker, and by conductor K from the third circuit breaker back to the generator. It will thus be seen that when any one of the doors is left unlocked, the corresponding circuit breaker will automatically interrupt the circuit to the controller and prevent the car from being moved until said door has been closed and locked. It will be understood that when the door is closed, it engages the projecting spring leaf E and depresses the same to close the circuit. If the door is not locked or secured, however, the resiliency of the leaf will force the door open again far enough to break the circuit. In other words, it is necessary to lock or secure the door in closed position in order to maintain a closed circuit. Consequently, all danger from accidents due to elevator doors being left unlocked is effectually avoided.

45 Referring to Figs. 2 and 3, within the casing of each circuit breaker there is a partition L to which the terminal contacts M, M' are secured in spaced relation, the same being suitably insulated from said partition, as at m, m'. Intermediate of said contacts, the partition is perforated, as at N. The spring leaf E is secured at one end to the outer surface of the casing and is normally pressed outward by a spring O coiled about a guide pin P the outer end of which engages said leaf near its attached end and extends through the wall of the casing and also through the partition L, see Fig. 2. The spring O abuts at one end against the partition and at the other end against a nut Q which is adjustable on the pin P for the purpose of varying the tension of the spring. The pin P is provided with an adjustable nut R, or other obstruction, on the opposite side of the partition from the spring, for limiting the outward movement of said pin and the leaf E. The adjustability of the

but R permits the normal angle of the spring leaf E with respect to the casing to be regulated to suit different doors and locks.

5 Attached to the leaf E near its free end is a guide pin S extending into the casing and through the perforation N in the partition L. Mounted to slide on said pin S is a bridging plate T normally arranged opposite but out of contact with the terminals M and M'. The bridging plate T is backed by an insulating plate T' and is adapted to slide along the guide pin S against the influence of a spring U for equalizing the pressure of said plate upon both terminals when the leaf E is pressed in. Said bridging or contact plate T is also insulated from the pin S by a fiber bushing s, see Fig. 3. The insulating plate T' projects beyond the contact or bridging plate T all around its edge, so as to prevent said latter plate from short circuiting with the walls of the casing. The spring U may be coiled around the pin S so as to abut at one end against the plate T for normally holding the same against the washer V which abuts against a shoulder V' formed at the proper point on said pin, while the other end of said spring abuts against an adjustable nut W mounted on a threaded portion W' of the pin. As indicated in dotted lines in Fig. 2, when the leaf E is pressed in, the bridging plate T will first come in contact with the terminals M and M' and then be forcibly held with equal pressure against both of said terminals by the contraction of the spring U as the leaf reaches its fully pressed in position.

10 The inner end of the pin S is guided in the opening N in the partition during its movement. The inner end of the pin P is projected slightly beyond the partition L by the inward movement of the leaf E, the spring O being thus contracted and its tension consequently increased so that it will automatically move the leaf outward again to break the circuit as soon as said leaf is released by the unlocking of the door to the elevator shaft.

15 Having thus described my invention, what I claim as new and desire to secure by Letters Patent of the United States, is:

20 A circuit breaker comprising a casing, a partition therein, a pair of spaced terminals, a bridging plate carried by the leaf and adapted to engage said terminals when the leaf is depressed, a pin carried by the leaf and extending through the partition, an adjustable stop on the inner end portion of said pin for limiting the outward movement of the leaf, an abutment on said pin, and a spring interposed between said abutment and the partition for the purpose specified.

25 In testimony whereof I have signed my name to this specification in the presence of two attesting witnesses.

JOHN J. KUNTZ.
